UNITED STATES PATENT OFFICE.

ALBERT SCHMID, OF ALLEGHENY, ASSIGNOR TO THE WESTINGHOUSE ELECTRIC COMPANY, OF PITTSBURG, PENNSYLVANIA.

ELECTRIC MACHINE.

SPECIFICATION forming part of Letters Patent No. 416,240, dated December 3, 1889.

Application filed April 2, 1889. Serial No. 305,652. (No model.)

To all whom it may concern:

Be it known that I, ALBERT SCHMID, a citizen of the Republic of Switzerland, residing in Allegheny, county of Allegheny, and 5 State of Pennsylvania, have invented a certain new and useful Improvement in the Construction of Electric Machines, of which the following is a specification.

The invention relates to the construction 10 of electric machines, and involves certain improvements in the machines themselves and in the method of building the same.

The object of the invention is to provide an efficient form of machine having a laminated field-magnet and armature-cores which 15 will not develop excessive heat when in operation, to simplify and cheapen the construction, and to generally adapt it to commercial use.

20 In carrying the invention into practice the machine is constructed in the following general manner, reference being had, especially in the description, to the construction of an alfernating-current machine—either a 25 generator or a motor. Plates or sheets of magnetizable material are first stamped into the proper size and shape, dependent upon the exterior configuration of the machine. In the present instance the circular form is 30 adopted. A hole or opening is stamped through the center of the sheet, and this ultimately receives the armature-shaft. Other openings are stamped in the plates, leaving intermediate webs, which are to form the 35

pole-pieces of the field-magnet. In case it is desired that the armature of the machine shall have magnetic lugs or teeth the openings in each sheet are of such size as to extend into the portion of the sheet forming 40 the armature-plate. The armature-plates are built up or assembled upon an armature-shaft and bound together and turned or trimmed to the proper size. They may be previously stamped with openings for ventilation and oxidized or annealed. The ring of the outer portion, having inwardly-projecting teeth, is cut in half, and these halves are laid up or assembled on a suitable mandrel and bound together. This portion may be 45 oxidized or annealed before this is done. They are then placed in a suitable field-magnet frame and permanently secured in position. The inner end of the resultant

pole-pieces may be bored out for clearance of the armature. The frame is made in sections corresponding to the halves of the field-magnet plates, so that the upper portion may be first placed over the field-magnet plates secured thereto and afterward removed from the lower portion, together with the upper 55 half of the plates, for the insertion of the armature. The armature itself is provided with coils, which, in case teeth are applied to the armature, surround or are placed over the teeth and bound in position.

60 The details will be more fully described in connection with the accompanying drawings.

In the drawings, Figure 1 is an elevation, partly in section, of a complete machine; and Figs. 2, 3, 4, and 5 illustrate steps in the construction of the machine.

65 Referring to the figures, A represents the frame of the machine. It is constructed in two sections a' a'' , and the former supports or carries the pillars a^3 a^4 , which carry the 70 bearings for the armature-shaft. The other section a^2 rests upon section a' , but is removable therefrom. The frame holds the field-magnet core C, which is built up of plates of magnetizable material. The armature-core is also built up of laminæ or plates 75 of the same material. The armature-plates are themselves cut out from the sheets of which the field-magnet plates are made. In other words, that which would otherwise be 80 refuse in constructing the field-magnet plates is utilized in constructing the armature.

85 The method of forming the plates for both the field-magnet and armature is as follows: A sheet of magnetizable material of the required size and convenient shape—for instance, 90 square—is first stamped or cut into circular or other desired shape, and by the same operation a hole c may be formed in the center. (See Figs. 3 and 4.) By accomplishing these 95 two results by one operation it is easily insured that the hole shall be in the center of the plate. After this operation, or, if desired, simultaneously therewith, the holes c' c' are stamped at equal distances through 100 the plates. These are separated the proper distances to leave teeth or webs d , which are to form the pole-pieces of the field-magnet. The shape of the holes is such that the opposite sides of the webs are parallel, or approximately so. The holes extend as near the 105

outer surface or edge of the plate as it is desired to have the metal of the field-magnet core cut away. The central portion of the plate is then stamped out, as shown by the dotted line in Fig. 3. The portion thus cut out is utilized as an armature-plate. If it is desired that the armature shall have teeth or projections, then the openings *c'* extend inward a distance sufficient to cut away the metal between such teeth, as represented at *f'* in Fig. 3. The dotted line *f* then cuts through merely the web. During one of the stamping operations holes *h* are cut into the field-magnet plates. These are for convenience in binding the plates together in their proper relative positions. The field-magnet plates are then cut in half, as indicated by the dotted lines *h'*, one portion being designed to be used in the lower half of the field-magnet and the other in the upper half. The field-magnet plates are laid upon a mandrel provided with rods, over which the openings *h* are placed, and the plates are built up one upon another until the entire number is assembled. They are firmly clamped together, and the entire mass is then placed in the lower half of the field-magnet frame. The shaft of the mandrel is concentric with the center of the field-magnet, and therefore rests in the bearings of the armature-shaft. The upper section of the field-magnet frame is then applied. The plates of the field-magnet are fastened into the respective sections of the frame by flanges *a⁵* upon the frame and by bolts and by pouring molten metal or cement in the openings *n*, provided in the field-magnet frame. The plates of the field-magnet may be cut away during the process of preparation at the points *m* for the purpose of receiving this metal or cement. By thus fastening the frame and core together the latter is effectually prevented from shifting. In assembling the sections of the field-magnet plates they are brought into their former relative positions—that is to say, making complete rings. After they have been placed in the ring and fastened in position the mandrel may be withdrawn. The clamp being released, the plates are prevented from forcing themselves apart by the overhanging flanges *a⁵* of the field-magnet frame. Bolts *p* may be inserted through the openings *h* to hold the pole-pieces firm. It is usually desired to place thicker plates *H* at the respective sides of the field-magnet core. The bolts *p* may bind these in position. The entire interior may then be bored out to render the inner ends of the pole-pieces true and even. The upper section of the frame, with its laminated field-poles, is then removed from the lower section. The field-magnet bobbins *t* are then slipped over the pole-pieces and fastened by bolts, pins, or screws.

The armature-plates, either before or after being separated from the field-magnet plates,

are stamped with openings *k* for the purpose of ventilation and removing useless metal. In assembling the plates these openings may be brought opposite each other or set so as to overlap, thus exposing an increased radiating-surface within the armature. After the armature is in position the upper portion of the field-magnet is again placed in position 75 upon the lower half.

I claim as my invention—

1. A field-magnet for electric machines, consisting of two sets of laminæ semicircular in form and a divided field-magnet frame, one 80 portion receiving one set of the laminæ and the other the other set of the laminæ.

2. The combination of the lower and upper halves of the field-magnet frame and the laminæ forming the field-magnet, divided in 85 halves and bound in their respective sections of the frame.

3. The combination of a field-magnet frame and laminæ for composing the field-magnet bound within such frame, said frame having 90 openings into which molten metal or cement may be poured for binding the parts together.

4. In a field-magnet for electric machines, a frame of cast-iron having parallel flanges, 95 both of which are integral with the body of the frame, and laminæ composing the field-magnet poles bound in the frame by and between said flanges and secured or cemented by molten metal or cement, substantially as 100 described.

5. A field-magnet for electric machines, composed of a frame having two flanges, both integral therewith and laminæ bound between said flanges, substantially as described. 105

6. A plate for constructing laminæ for electric machines, stamped with radiating openings, leaving webs for pole-pieces of the field-magnet, and also stamped with a central opening for receiving the armature-shaft. 110

7. A plate for constructing laminæ for electric machines, stamped with radiating openings, leaving webs for the pole-pieces of the field-magnet, and with a central opening for receiving the armature-shaft, and with 115 openings for receiving bolts.

8. The hereinbefore-described method of building electric machines, which consists in stamping the laminæ for composing the field-magnet from plates of soft iron, dividing the field-magnet plates so stamped, assembling and binding the respective sets of sections in position, temporarily removing the one set from the other and placing the armature in position, and subsequently replacing the 120 removed set of sections.

In testimony whereof I have hereunto subscribed my name this 30th day of March, A. D. 1889.

ALBERT SCHIMID.
